US00D396091S

United States Patent [19]

Jomha

[11] Patent Number: Des. 396,091

[45] Date of Patent: **Jul. 14, 1998

[54] FLAP VALVE ACTUATOR FOR A TOILET TANK

[76] Inventor: Mohamed Ahmed Jomha, 15355 - 116 Avenue, Edmonton, Alberta, Canada, T5M 3Z5

[**] Term: 14 Years

[21] Appl. No.: 43,624

[22] Filed: Sep. 8, 1995

[51] LOC (6) Cl. 23-01

[52] U.S. Cl. D23/258

[58] Field of Search D23/236, 258; 4/324, 391, 405, 415, 378, 392

[57] CLAIM

The ornamental design for a flap valve actuator for a toilet tank, as shown and described.

DESCRIPTION

FIG. 1 is a perspective view of a flap valve actuator showing a first embodiment of my design;

FIG. 2 is an elevational view seen from the right side of FIG. 1;

FIG. 3 is an elevational view seen from the opposite side of FIG. 2;

FIG. 4 is an elevational view seen from the right side of FIG. 2;

FIG. 5 is a top plan view thereof;

FIG. 6 is a bottom plan view thereof;

FIG. 7 is a perspective view of a second embodiment of my design;

FIG. 8 is an elevational view seen from the right side of FIG. 7;

FIG. 9 is an elevational view seen from the opposite side of FIG. 8;

FIG. 10 is an elevational view seen from the right side of FIG. 8;

FIG. 11 is a top plan view thereof; and,

FIG. 12 is a bottom plan view thereof.

The undisclosed inner surface of the upper half section of the flap valve actuator forms no part of the claim design.
